(57) **CLAIM**

The ornamental design for an observation tower with movable viewing platform as shown and described.

DESCRIPTION

FIG. 1 is an isometric view of an observation tower with movable viewing platform.

FIG. 2 is a front side elevation view thereof, the back side being a mirror image thereof.

FIG. 3 is a left side elevation view thereof, the right side being identical.

FIG. 4 is a perspective view of the viewing platform being in the lowered position, it being understood that the viewing platform could be at any location along the support pillars. All other surfaces being the same as the other.

FIG. 5 is an enlarged partial front elevation view of FIG. 2. FIG. 6 is a top plan view thereof.

FIG. 7 is an enlarged, partial view showing the upper portion of FIG. 1; and,

FIG. 8 is a further enlarged, partial view showing the upper portion of FIG. 1.

The broken lines illustrate portions of the observation tower with moveable platform that form no part of the claimed design. The dot-dash lines of FIGS. 5, 7 and 8 depict the boundaries of the enlargements and form no part of the claimed design.

1 Claim, 8 Drawing Sheets
